TION OF DELAWARE.

FLUID-CONTROL VALVE.

1,311,536.

Specification of Letters Patent. Patented July 29, 1919.

Application filed December 10, 1918. Serial No. 266,037.

To all whom it may concern:

Be it known that I, CHARLES H. SMOOT, a citizen of the United States, and resident of South Orange, in the county of Essex and 5 State of New Jersey, have invented certain new and useful Improvements in Fluid-Control Valves, of which the following is a specification.

My invention relates in general to the regulation of pressure or volume of gases automatically as where for example, uniform pressure or volume is to be maintained in a moving body of gas. The general principles of such an apparatus have already been 10 set forth in my prior application filed March 25th, 1918, Serial No. 224,622, and it is in apparatus of the general type therein shown that the present invention constitutes an improvement. The particular improvement 15 contemplated, comprises certain inter-connections between the control valve actuating member and the relief valve which controls the preponderance of fluid pressure to which the control valve actuating member is subjected.

A simple embodiment of one form of the invention comprising the improved feature, will suffice to make clear to those skilled in the art, the manner in which the improvement 20 may be applied in practice.

The accompanying drawing shows diagrammatically in central vertical section sufficient of the complete system to enable the principles of the invention to be clearly 25 understood.

In said drawing, "E" indicates the main or pipe, constituting the passage-way for fluid, the pressure or volume of which is to be controlled by means of a balanced control valve "L", under the influence of pressure responsive valve actuating member "I", here shown in the form of a diaphragm.

For applying operating fluid to the chamber beneath diaphragm "I", a pipe or by-pass "B" may be led off for example from the main "E", said pipe "B" communicating with the chamber beneath diaphragm "I" and also having a by-pass passage leading to relief valve "F", which controls the escape of fluid from the by-pass into pipe "K" leading back to the low pressure side of valve "L" in pipe or main "E". The admission of fluid into the pipe "B" is restricted by adjustable valve "D" so that a

drop in pressure occurs in the passage of the 55 fluid therethrough, as long as the by-pass valve "F" is off its seat to permit the escape or relief of fluid from the pipe "B". Obviously, an increase of pressure under diaphragm "I" tends to close valve "L". 60 Weights "H" are employed for example to hold the valve "L" open up to a prescribed pressure within the chamber beneath the diaphragm "I". This chamber, I may term the metering chamber, as it contains the 65 parts which actuate the control valve "L" to derive a measured pressure at the right of valve "L" in the main "E".

In my said prior application, I have shown in principle, the relief valve "F" for 70 varying the preponderance of pressure in the metering chamber. In the said prior application the relief valve is mechanically free and disconnected from the control valve actuating member, but is exposed as 75 in the present case, to the lifting effect of a pressure to which the said actuating member is also exposed. Furthermore, both in the former invention and in the present invention, a multiplying effect upon the actuation of the relief valve is obtained by a 80 pressure, derived from the fluid to be regulated, applied to a multiplied area of surface on a part which controls the position of the relief valve. In the present case, this 85 multiplied surface is seen in the diaphragm "G" exposed to a pressure corresponding with the low pressure side of valve "L" in the main "E". When this pressure is below 90 normal the relief valve "F" is more open so that pressure in the metering chamber being more relieved, the valve "L" is opened.

It will be understood that valve "F" is counter-weighted at "C" to hold it off its seat up to a given pressure in the pipe "K". 95

Under some conditions of pressure variation, the valve "F" would vibrate and cause a corresponding vibration of the main valve actuating mechanism, if mechanically independent of the latter. To correct this tendency, the present invention provides a yielding inter-connection between the relief valve "F" and the diaphragm "I" in the form of a dash pot and piston "J," as shown in the drawing. This interconnection is in effect, 100 an elastic inertia or stabilizing device, as sudden movement of either the relief valve or the diaphragm independently of the 105

other is prevented by the dash pot action and movement of the two parts in unison is prevented by the opposed efforts of their actuating pressures. Their responsive tendencies, when arranged as shown, are opposite in direction, and yieldingly restrained by the action of the dash pot interconnection. That is to say, sudden drop of pressure at the right of valve "L" cannot suddenly permit valve "F" to rise farther off its seat without in the same act applying, through the elastic inter-connection, a yielding upward pull on valve "L" which restrains or retards the response of the latter to the pressure change in the metering chamber. A more gradual and a smoother change in the position of valve "F" is however, permitted by the escape of air from the dash pot device "J."

In a regulator of the type herein referred to, a much improved operation is obtained if the regulating valve opens and closes at a rate or velocity which bears a definite relation to the amount or extent to which the regulated pressure has departed from normal. By means of the dash pot mechanism "J," the velocity of continued movement of the regulation valve "F" in either direction is automatically varied for different departures of the regulated pressure from normal on the multiplying diaphragm "G." A larger departure from normal pressure on diaphragm "G" produces a more rapid motion of control valve "L," which motion is just sufficient to produce from the dash pot "J" a total force on diaphragm "G" equal and opposite to the departure from normal of the pressure on "G." Small departures from normal value of pressure on diaphragm "G" give definitive but slow velocity on control valve "L" while larger departures give more rapid motion to the control valve. The dash pot therefore, directly meters the relation between velocity of control valve movement and the extent of departure from normal value in the pressure to be regulated. Momentary departure from normal, thus does not produce substantially any variation in the position of the control valve.

I claim:

1. A fluid pressure regulator comprising in combination a control valve for the fluid, a pressure responsive actuating means therefor, means for admitting a restricted supply of operating fluid to said actuating means, a

relief valve exposed to the lifting effect of the operating fluid and permitting a measured escape thereof, to control the pressure on the said actuating means, and a yielding interconnection between said relief valve and said actuating means to transmit a retarding force to the movement of one in response to the other.

2. A fluid pressure regulator comprising in combination a fluid conduit, a control valve therein, a pressure responsive actuating means therefor, means for admitting a restricted supply of operating fluid to said actuating means, a relief valve controlling the escape of operating fluid therefrom to determine the pressure upon said actuating means, means exposed to the pressure to be regulated for controlling the position of said relief valve, and a yielding interconnection between said actuating means and said relief valve to retard the response of the one to the other.

3. A fluid pressure regulator comprising in combination a fluid conduit, a control valve therein, a pressure responsive actuating means therefor, means for admitting a restricted supply of operating fluid to said actuating means, a relief valve controlling the escape of operating fluid therefrom to determine the pressure upon said actuating means, means exposed to the pressure to be regulated for controlling the position of said relief valve, and a yielding interconnection between said actuating means and said relief valve for automatically controlling the velocity of response of the control valve to changes of regulated pressure depending on the extent of change.

4. A fluid pressure regulator comprising in combination a fluid conduit, a control valve therein, a pressure responsive actuating means therefor, means for admitting a restricted supply of operating fluid, to said actuating means, a relief valve controlling the escape of operating fluid therefrom to determine the pressure upon said actuating means, means exposed to the pressure to be regulated for controlling the position of said relief valve, and a dash pot interconnecting said relief valve and the control valve actuating means, to render response of the latter dependent in velocity upon the extent of change in the regulated pressure.

CHARLES H. SMOOT.
